UNITED STATES PATENT OFFICE.

HERMAN H. TOLL, OF CLARINDA, IOWA, ASSIGNOR TO CLARINDA LAWN MOWER COMPANY, OF CLARINDA, IOWA, A CORPORATION OF IOWA.

DRIVING MECHANISM FOR POWER WASHING-MACHINES.

1,339,587.

Specification of Letters Patent. Patented May 11, 1920.

Application filed November 26, 1917. Serial No. 204,072.

To all whom it may concern:

Be it known that I, HERMAN H. TOLL, citizen of the United States of America, and resident of Clarinda, Page county, Iowa, have invented a new and useful Driving Mechanism for Power Washing-Machines, of which the following is a specification.

The object of this invention is to provide an improved construction and arrangement for driving mechanism for power washing machines.

A further object of this invention is to provide an improved, unitary, compact driving mechanism for power washing machines.

15 A further object of this invention is to provide an improved driving mechanism for power washing machines, which mechanism comprises a compact assembly carried in a restricted area and in intimately associated 20 relations on the support.

25 A further object of this invention is to provide improved means for transmitting power through a driving shaft from the prime mover to a countershaft designed in turn to transform the continuous rotary motion to an alternating rotary motion.

30 My invention consists in the construction, arrangement and combination of elements hereinafter set forth, pointed out in my claims and illustrated by the accompanying drawing, in which—

35 Figure 1 is a side elevation of a power washing machine embodying my improvements. Fig. 2 is a plan of the same. Fig. 3 is a side elevation at right angles to Fig. 1, a portion of the support being broken away. Fig. 4 is a horizontal section of certain portions of the driving mechanism, substantially on the line 4—4 of Fig. 1, on an enlarged scale.

40 Fig. 5 is a detail side elevation showing a modified form of connection of the motor supporting bracket to the support.

45 In the construction of the mechanism as shown the numeral 10 designates generally a support such as a tub carried by legs 11 preferably resting on a skeleton platform 12 provided with swivel casters 13. The tub 10 is formed with a fixed cover member 14 and a movable cover member 15, relatively 50 larger than said fixed cover member and suitably hinged as hereinafter set forth and also provided with suitable latching devices 16 of any desired character. A supporting plate 17 is mounted on and suitably secured

as by bolting to the fixed cover member 14 and said plate preferably is of substantially the same dimensions in length and width as said cover member, except that it is of substantially uniform width throughout its 60 length, while said cover member generally is segmental in plan, the combined cover members 14 and 15 being of circular form. The supporting plate 17 is formed with spaced, integral, upstanding bearing brackets 18, 19 near its ends and a driving shaft 20 has its bearings in upper portions of said brackets, extending longitudinally of and above the fixed cover member 14 and in a vertical plane corresponding approximately 70 with the outer margin of said cover member. The supporting plate 17 and bearing brackets 18, 19, together with other members hereinafter referred to as integrally formed with said plate, preferably are formed in 75 one piece from metal by molding or casting. Hinge members 21, 22 are secured to the top of the movable cover member 15, as by bolts 23, extend upwardly and outwardly beyond a margin of said cover member, and have bearings at their upper ends on the driving shaft 20, thus providing a pivotal connection of said movable cover member to the support, the axis of articulation being removed laterally and vertically 80 from the joining line between the cover members 14, 15. At their outer ends the hinge members 21, 22 are formed with inclined shoulders or stops 24, shown particularly in Fig. 1, adapted to engage vertical 85 ribs or flanges 25 on the brackets 18, 19, for the purpose of stopping outward movement of the movable cover member and holding the same in open position inclined outwardly from a vertical plane. A latching 90 bar 26 may be pivoted on the bracket 18 and engage a shoulder or stop 27 on the hinge member 21, when the movable cover member 15 is in open position, to prevent accidental dropping or closing of said cover 95 member.

95 A motor bracket 28 is mounted on the side of the support adjacent to the fixed cover member 14, and secured thereto as by bolts 29. The bracket 28 also may be connected to the supporting plate 17 by a metal strap or link 30. An electric motor 31 is provided and is adapted to rest loosely on the bracket 28, a cushion 32 preferably being provided on the outer end of said bracket 110

to receive said motor. The motor shaft 33 is provided with a worm (not shown) at its inner end meshing with and adapted to drive a worm gear 34 fixed to the driving shaft 20. This construction is shown and described in detail in Letters Patent of the United States Number 1,228,887 granted Clarinda Lawn Mower Company June 5, 1917 on the application of Andrew J. Dinkel, 10 to which patent reference hereby is made. A housing 35 incloses the projecting portion of the power shaft 33 and worm thereon as well as the lower portion of the worm gear 34, and a removable cap 36 for said 15 housing normally covers the upper portion of said gear. The cap 36 separates from the housing 35 on the horizontal plane of the axis of the shaft 20 and said cap and housing are together formed with bearings 37 20 in which said shaft is journaled. The motor 31 and members carried thereby are adapted for oscillation through an arc over the upper portion of and articulating on the shaft 20 as an axis, the bearings 37 25 turning on said shaft and the worm traveling around the worm gear 34 in such movement, so that the motor may at times be moved over the movable cover member 15, where it will be more centrally located relative to the support.

A gear housing 38 is provided which incloses the major portion of the driving shaft 20 between the housing 35-36 and the bracket 19, and said housing is formed in 35 two parts separable on a vertical plane and secured by screws 39. A stub shaft 40 is mounted in the housing 38 at right angles to the shaft 20 and is journaled in said housing. A bevel gear 41 is fixed to the 40 driving shaft 20 within the housing 38 and meshes with and is adapted to drive a bevel gear 42 fixed to the stub shaft 40. (Fig. 4.) A countershaft 43 is journaled in and projects at one end from the housing 38 and is 45 arranged at right angles to and below the plane of the driving shaft 20, and a spur gear 44 is mounted loosely on said countershaft and meshes with and is adapted to be driven by a spur gear 45 fixed to the stub shaft 40. The countershaft 43 projects at 50 its inner end from the housing 38 above the movable cover member 15 and enters a dolly gear box 46 carried by the central portion of said cover member. A vertical dolly shaft is mounted for vertical sliding movement and for alternating rotary motion 55 through the dolly gear box 46, and carries a knob or head 47 on its upper end above said box. The dolly shaft also projects within 60 in the support or tub 10, when the cover member 15 is in closed position, and is provided with suitable agitating devices of common form (not shown). Any suitable driving connections between the counter- 65 shaft 43 and dolly shaft may be employed, to

transform continuous rotary motion of the countershaft to alternating rotary motion of the dolly shaft; examples of such connections being shown and described in Letters Patent of the United States Number 70 1,135,496, granted April 13, 1915 on the application of Levi Brown, and Number 1,228,887, granted June 5, 1917 on the application of Andrew J. Dinkel, to which 75 patents reference hereby is made.

A clutch member 48 is fixed to the spur gear 44 and is adapted to be engaged at times by a clutch member 49 feathered on the shaft 43, to effect rotation of said shaft through the gear 44 and connections. The 80 sliding clutch member 49 is formed with the usual circumferential groove in which rests loosely a yoke 50 having a stem 51 extending parallel with the countershaft 43 and extending slidably through the inner 85 end of the casing 38. A bell-crank lever 52 is fulcrumed by a pin 61 on the outer end of the stem 51 and is adapted for manual oscillation to reciprocate said stem and slide the clutch member 49 on the countershaft 90 43, into and out of engagement with the clutch member 48. It is to be understood that any suitable type of clutch may be employed in this construction. An expansive coil spring 53 preferably is coiled on 95 the stem 51 within the casing and serves as a positive means for effecting engagement of the clutch members when the lever 52 is thrown to the position shown in Fig. 4.

A cam finger 54 may be fixed at one end 100 to the supporting plate 17 and extend inwardly and upwardly therefrom on a curve so arranged that when the movable cover member 15 is moved to open position said finger will be engaged, if the lever 52 is in 105 position shown, whereby the clutch devices are in engagement for the operation of the dolly shaft, by said lever and the lever moved to the opposite or inoperative position, thereby automatically throwing the 110 dolly shaft out of gear whenever the tub is opened.

The casing or housing 38 is formed at its ends with bearings 55 fitting closely to and rotatable upon the driving shaft 20, and 115 when the movable cover member 15 is oscillated said casing and members carried thereby and therein oscillate upon said shaft, the gear 42 rotating upon the gear 41 in such movement.

End portions of the driving shaft 20, beyond the housings 35 and 38, and in the portions having bearings in the brackets 18, 19 and hinge members 21, 22, are inclosed by sleeves 56, 57. Similarly the portion of the 125 countershaft 43 between the casing 38 and dolly gear box 46 is inclosed by a sleeve 58. Thus all moving parts of the driving mechanism, with the exception of the head or knob 47 of the dolly shaft, are inclosed.

The driving shaft 20 preferably is extended forwardly beyond the bearing 19 and is designed, through driving and controlling mechanism indicated generally by the numeral 59, to operate a wringer mechanism 60. This wringer-driving and controlling mechanism forms no part of my present invention, but is the subject matter of my companion application executed on even date 10 herewith filed November 26, 1917, Serial Number 204,073, to which application reference hereby is made.

Attention is called to the fact that all of the mechanism for transmitting power from 15 the motor to the follower devices (dolly and wringer mechanism) is arranged in a compact assembly, which, including also the motor itself, is located on, adjacent to and connected with the supporting plate 17, 20 which in turn is removably carried by the relatively small fixed cover member 14. The entire mechanism thus may be removed and replaced relative to a support by the manipulation of a very few bolts or screws. This 25 compact arrangement of the mechanism also facilitates complete inclosure of the driving parts by relatively small housings or casings, thus insuring safety to those engaged in operating the device.

30 In Fig. 5 is shown a modified construction in fragmentary form, in which the motor bracket 28^a is formed integrally on and depends from the supporting plate 17^a, through an integral connecting portion 30^a.

35 The mechanism, being located entirely on top of the support, is easy of access for repair, oiling or the like. Being compactly arranged and intimately associated, through the supporting plate 17, facilitates and insures proper assembly of the mechanism on 40 the support when separately shipped, and also facilitates packing the driving mechanism in small compass.

I claim as my invention—

45 1. In a device of the class described, a support, a driving shaft journaled thereon, a source of power carried by said support and provided with driving connections to said driving shaft, a housing inclosing and 50 having bearings on said driving shaft, a countershaft journaled in and projecting beyond said housing, a stub shaft journaled in said housing parallel with said counter- 55 shaft, bevel gear connections between said driving shaft and the stub shaft, and clutch- controlled spur gear connections between 60 said stub shaft and the countershaft.

2. In a device of the class described, a support, a driving shaft journaled thereon, 65 a source of power carried by said support and provided with driving connections to said driving shaft, a housing inclosing a portion of and having bearings on said driv- ing shaft, a countershaft journaled in and 70 projecting beyond said housing, a stub shaft

75 journaled in said housing parallel with said countershaft, bevel gear connections between said driving shaft and stub shaft, a spur gear fixed to said stub shaft, a spur gear loosely mounted on said countershaft 70 in mesh with the first spur gear, said loosely mounted spur gear being formed with a clutch member, a coacting clutch member feathered on said countershaft, and means for sliding the latter clutch member. 75

3. In a device of the class described, a support, a fixed cover member and a movable cover member thereon, a supporting plate fixed to said fixed cover member, brackets on and rising from said support- 80 ing plate, a driving shaft journaled in said bracket, and hinge members fixed to and extending upwardly and outwardly from said movable cover member and pivoted on said driving shaft, said brackets being 85 formed with vertically arranged ribs, said hinge members being formed at their pivoted ends with lips adapted to engage said ribs and limit outward movement of said movable cover member. 90

4. In a device of the class described, a support, a fixed cover member and a movable cover member thereon, a supporting plate fixed to said fixed cover member, brackets on and rising from said support- 95 ing plate, a driving shaft journaled in said brackets, one of said brackets being formed with a vertically arranged rib, hinge members on and extending outwardly and up- 100 wardly from said movable cover member and pivoted on said driving shaft, one of said hinge members being formed at its pivoted end with a lip adapted to engage said vertical rib and limit outward move- 105 ment of the movable cover member, one of said hinge members being formed with a shoulder intermediate of its ends, and a latching bar pivoted on said supporting plate and adapted to engage said shoulder 110 when the movable cover member is in open position.

5. In a device of the class described, a support, a driving shaft thereon, means for operating said driving shaft, a movable cover member hinged on said support and carrying a follower device, a countershaft arranged on said support, extending over said movable cover member and adapted to operate said follower device, clutch-con- 115 trolled driving connections between said driving shaft and countershaft, a bell-crank lever fulcrumed on a vertical axis and adapted to control the clutch-driving connec- 120 tions, and a cam finger fixed to said support and adapted to be engaged by said bell-crank lever when the cover member is moved to open position, whereby said bell-crank lever is oscillated to disconnect said clutch connections. 125

6. In a device of the class described, a 130

support having a hinged cover member, a driving shaft mounted on said support, a source of power adjacent to said shaft on said support and adapted to operate said driving shaft, a follower device carried by said cover member, a countershaft adapted to transmit power to said follower device, a stub shaft journaled on said support, driving connections between the driving shaft and stub shaft, a gear fixed to said stub shaft, a gear loosely mounted on said counter shaft and meshing with the first gear,

the loosely mounted gear being formed with a clutch member, a clutch member slidably mounted on the countershaft and adapted to coact with the first clutch member, yielding means tending to hold the sliding clutch member in engagement with the other clutch member, and means for moving the sliding clutch member out of engagement with the other clutch member.

Signed by me at Clarinda, Iowa, this 18th day of July, 1917.

HERMAN H. TOLL.
